UNITED STATES PATENT OFFICE

RUDOLF G. BERTHOLD, OF BERLIN-SIEMENSSTADT, GERMANY, ASSIGNOR TO WESTING-HOUSE ELECTRIC & MANUFACTURING COMPANY, A CORPORATION OF PENNSYLVANIA

VACUUM TUBE

Application filed June 23, 1925, Serial No. 38,962, and in Germany July 26, 1924.

This invention relates to vacuum tube devices. Particularly, the invention relates to means for heating the cathode in such devices.

5 It is an object of this invention to provide means whereby the cathode may be heated by a stream of electrons from an auxiliary electron source.

10 It is another object of this invention to provide such an arrangement that the face of the cathode which is thus heated is toward the anode.

15 It is a further object of this invention to provide a cathode of large thermal capacity and relatively small thermal conductivity and which is heated at only a small portion of the surface.

20 It is a still further object of this invention to provide an arrangement in which a portion of the cathode may be heated to or beyond the melting point without destroying the cathode.

25 Any suitable material may be employed for the cathode, for instance, tungsten. It may be heated in any suitable manner as, for instance, by a bombardment thereof with electrons from a second source.

30 One form of device embodying the invention is illustrated in the drawing. The single figure of the drawing is a vertical section through the device showing, in a partially diagrammatic way, the arrangement of the several parts.

35 The main source of electrons is a cathode 1, of conical shape located opposite the anode 2. A plate battery 3 is shown in the drawing in order to indicate that the electrode 2 is the anode and the electrode 1 is the cathode. The anode has the form of a large bell having a horizontal base.

40 A second electron source 4 is located on the opposite side of the anode from the cathode. It has a lower potential than the cathode 1, whereby it projects electrons against the central portion of the surface 5. The potential difference between the source 4 and the cathode 1 is indicated in the drawing by the battery 6. The heating of the electrode 4 is indicated on the drawing by

the battery 7. Any other source of heating current may, however, be used.

5 If the central portion of the surface 5 is heated to such a degree that it softens or even melts, no damage will result, as the 55 cooler rim portion maintains the softer or fluid central portion in its proper operative position. The heating may even be carried far enough to melt the central portion of the surface 5, in order to provide as many electrons as possible.

60 The heated surface is not necessarily located in a horizontal position, but, if it is not, the heating may not be carried to the melting point, but only so far that the bombarded portion of the surface becomes softened only. It may be heated until the surrounding cooler portions just suffice to retain it. Tungsten is well adapted for such purpose.

65 A part of the surface may be permitted to melt, even when the cathode surface is not horizontal, if the electrode is continuously rotated during use around an axis that is preferably at an angle of 90 degrees to the glowing surface. The molten material is thereby prevented from dropping off. The electrons from the source 4 are guided by suitable means such as blinders or other cover members, illustrated by the member 8 having an opening 9 therethrough.

70 Other forms of the invention will readily occur to those skilled in the art and the preceding detailed description is not intended as a limitation. What I desire to protect by Letters Patent is indicated by the following claim.

75 I claim as my invention:

80 An electron-discharge tube comprising a cathode at one end thereof, a means for generating electrons at the other end thereof, a 85 hollow anode next adjacent said cathode to receive secondary electrons emitted by said cathode, and an independent shield next adjacent said generating means and having a 90 perforation in alignment with said cathode and said generating means for the passage 95 of primary electrons to said cathode.

100 In testimony whereof, I have hereunto subscribed my name this 29th day of May, 1925.

RUDOLF G. BERTHOLD.
